WRINGER AND WASH TUBS UNIT

Donato J. Porreca, Philadelphia, Pa.

Application November 9, 1943, Serial No. 509,534

4 Claims. (Cl. 68—22)

1

This invention relates to a unitary combination of wash tubs and clothes wringer.

An important object of the invention is the provision of a wringer which is so combined with a pair of wash tubs that it may assume a position over and between the tubs when in use, but may be adjusted to a position within one of the tubs when not in use. With this arrangement, the wringer is adjusted into an out-of-the-way position and is taken out of sight when the tubs are covered. Thus, it is entirely practical for the tubs and wringer to be located in a modern kitchen without marring the pleasing appearance thereof.

A somewhat more detailed object of the invention is the provision of mechanism which permits this adjustment of the wringer. This mechanism must, of necessity, provide for a raising and lowering motion and a swinging motion. Particular features and advantages of the invention are associated with the provision of this mechanism.

Yet another object of the invention is the provision of an adjustable wringer, of the character aforesaid, which includes a drive to the top roller. This arrangement readily accommodates the feature of adjustability above referred to.

Various other more detailed objects and advantages of the invention, such as arise in connection with carrying out the above noted thoughts in a practical embodiment, will in part become apparent and in part be hereinafter stated, as the description of the invention proceeds.

The invention, therefore, comprises an adjustable wringer that is adapted to assume a service position above and between two tubs, and which may be swung out of this position and depressed into an out-of-the-way position within one of the tubs. The wringer is characterized by providing a drive to the top roller, and the bottom roller has a diametrical dimension at least twice as great as the top roller, whereby it is constituted a carrier or apron to feed the clothes to the bite of the wringer.

For a full and more complete understanding of the invention, reference may be had to the following description and accompanying drawing, wherein:

Figure 1 is a view of a kitchen cabinet, which may house a pair of wash tubs, together with an adjustable wringer designed in accordance with the precepts of this invention;

Figure 2 is a side view in elevation with some parts broken away, showing the cabinet open

2

and the wringer in service position. This view also develops, in dotted lines, the depressed out-of-the-way position of the wringer when not in use;

Figure 3 is a top plan view showing the relation of the wringer to the wash tubs; and

Figure 4 is an enlarged detailed showing of the wringer and associated supporting and driving mechanism.

Referring now to the drawings, wherein like reference characters denote corresponding parts, and first more particularly to Figure 1, a kitchen cabinet which may house a pair of washtubs and wringer such as provided by this invention is referred to in its entirety by the reference character C. The cabinet C includes a top comprising panels 10 and 11, which are hingedly connected together along the line 12, while the panel 10 is hingedly connected along the line 13 to the back designated 14. As is more clearly brought out in Figure 3, a pair of wash tubs 15 and 16 are housed within the cabinet C. These wash tubs 15 and 16 are substantially of duplicate construction, and they include abutting center walls 17 and 18 over which the wringer, to be herein-after described, is adapted to be positioned when in usable or service position. It will be noted that the corners of the wash tubs are rounded, and at the front of the wash tubs the rounded corners 17 and 18 provide a recess 19 which receives the wringer supporting mechanism. This recess 19 is closed by the front wall of the cabinet C that is identified at 20.

Referring now more particularly to Figure 4, it will be noted that carried on the inner face of the wall 20 and projecting into the recess 19 is a bracket 21 which provides spaced bearing elements 22 and 23. A vertically extending drive shaft 24 is journaled in the bearings 22 and 23, and, between these members, carries a sheave 25 in driving relation. That is, the sheave is provided with a square opening which receives a complementary shape of the drive shaft, or the sheave 25 may be otherwise keyed thereto.

A cylindrical casing 26 is positioned in the recess 19 and preferably is immovably anchored to the walls of the tubs 15 and 16. This casing 26 has a bottom 27 formed with an opening 28 through which extends the drive shaft 24. This opening 28 is continued up through a nipple 29 that is carried by the bottom wall 27. It will be noted that those portions of the drive shaft 24 which pass through the bearings 22 and 23 and the opening 28 in the bottom 27 and nipple 29 are 55 circular to provide for the rotation of the drive

shaft 24. However, above the nipple 29, the drive shaft 24 assumes a non-circular cross section such as the square shape depicted at 39 in Figure 4. This square portion 30 is slidably received in a shaft 31 having an outer cylindrical surface and a square recess as complementary to the square portion 30.

An inner casing member 32 is telescopically fitted within the casing 26 and has a top 33 formed integrally therewith, and which top is in turn formed with an opening 34 in which is journaled the shaft 31. This opening 34 is continued down through a downwardly extending nipple 35 that is formed integrally with the top wall 33. An expansion spring 36 is fitted at the top around the nipple 35 and at the bottom around the nipple 29. This spring is, of course, housed within the telescopic casings 26 and 32 and exerts a tendency normally maintaining the casing 32 in an up-raised position. This wall of this casing 32 may be formed with an opening or recess 37 which is adapted to receive the end of a detent 38 that is carried by an operating member 39 and normally held in effective position by a spring 40.

Preferably formed integrally with the casing 32 and top 33 is a gear housing 41 providing a chamber 42. The shaft 31 projects into the chamber 42 and keyed to its free end is a bevelled gear 43. A roller shaft 44 carries a complementary bevelled gear 45 that is keyed thereon. This roller shaft 44 is journaled in an opening in the end wall 46 of the gear housing 41. The wringer frame, referred to in its entirety by the reference character F, may be secured in any preferred manner to the gear housing 41, such as by being welded thereto. This wringer frame includes end pieces 47 and 48, as well as a top guard 49 and a bottom 50. The shaft 44 is journaled in openings in the end pieces 47 and 48 and therebetween carries the top wringer roller 51. The bottom wringer roller 52 is also journaled in the end pieces 47 and 48.

It is important to note that the bottom roller 52 has a diametrical dimension appreciably greater than that of the top roller 51. Thus, with the wringer in the usable position, depicted in Figure 2, the clothes may be placed on that portion of the wringer roller 52 which projects out beyond the top roller 51, and the bottom roller 52 will then function as a carrier or apron which feeds the clothes to the wringer.

The drive shaft 24 may be driven from any convenient source. One arrangement for driving the shaft 24 is shown at Figure 2, which illustrates an electric motor 53 as being housed by the cabinet C beneath the tubs, and a belt 54 passes over the sheave 25 and another sheave 55 carried by the drive shaft of the motor 53.

While the modus operandi of the above described mechanism is believed to be obvious, it may be briefly described by noting that when the wringer is not in use it will assume the dotted line position shown in Figure 2 and the cabinet C will be closed as illustrated in Figure 1. When one is desirous of using the wringer, the top panels 10 and 11 are folded back into the position shown at Figure 2 leaving the wash tubs 15 and 16 open. The detent 38 will now be withdrawn from the opening 56 in which it is received when the wringer is depressed, the operating member 39 being availed of for this purpose. The entire wringer assembly that is carried by the casing 32 will now be upraised due to the influence of the expansion spring 36, which may, if necessary, be aided by the manual force of the operator. When the wringer

assembly has reached the proper height, the detent 38 will be received in the opening 37 and held in this effective position by the spring 40. It is evident that this upward movement on the part of the wringer assembly is accommodated first by the sliding interfit between the shafts 24 and 31, and, secondly, by the telescopic relation between the casings 26 and 32. When the wringer assembly first reaches the desired height, it will assume the full line position shown in Figure 3. In this position, the detent 38 will not be received in the opening 37, because these elements will not yet have become aligned. However, when the wringer is swung over into the dotted line position of Figure 3, the detent 38 will snap into the recess 37 and maintain the wringer in its usable or service position. In this position, the motor 53 may be operated, and the shaft 24 will be driven by the drive belt 54. The shaft 24 in turn drives the shaft 31, and this shaft, through the bevelled gears 43 and 45, drives the roller shaft 44.

When it becomes desirable to restore the wringer to its out-of-the-way position within the cabinet C, the operating member 39 is availed of to withdraw the detent 38 from the recess 37. The wringer assembly may now be swung back into the full line position of Figure 3 and then depressed into the dotted line position of Figure 2. In this position, the detent 38 will snap into the recess 56 to maintain the depressed position.

While a preferred specific embodiment of the invention is hereinbefore set forth, it is to be clearly understood that the invention is not to be limited to the exact constructions illustrated and described, because various modifications of these details may be provided in putting the invention into practice, within the purview of the appended claims.

What is claimed is:

40. 1. In combination, a pair of abutting tub structures, a wringer mounting receiving recess at one end of the line of abutment of said tub structures and extending on each side thereof a wringer mounting column arranged in said recess with its vertical axis substantially intersecting said line of abutment, a wringer structure mounted on said mounting structure, a notch in the wall of one of said tub structures adjacent said recess, said mounting being adapted to carry said wringer into alignment with said line of abutment and the wall of one of said tub structures transverse to said line of abutment and into an intermediate position where a portion of said mounting structure may be received in said notch to confine said wringer within the marginal and vertical dimensions of one of said tub structures.

60. 2. In combination, a pair of abutting tub structures, a wringer mounting receiving recess at one end of the line of abutment of said tub structures and extending on each side thereof, an L-shaped wringer mounting column having its short leg lying in a plane transverse to the portion received in said recess, a wringer structure carried by said short leg of said mounting column, a notch adjacent said mounting receiving recess in the wall of one of said tub structures, said mounting column being adapted to carry said wringer into alignment with the line of abutment of said tub structures and the wall of one of said tub structures transverse to said line of abutment, as well as to an intermediate position to cause said short leg and said wringer to be received within the vertical and marginal confines of one of said tub structures for storage.

3. In combination, a pair of abutting tub structures, a wringer mounting receiving recess at one end of the line of abutment of said tub structures and extending on each side thereof, a wringer mounting column arranged in said recess with its vertical axis substantially intersecting said line of abutment, a wringer structure mounted on said mounting structure, said mounting being adapted to carry said wringer into alignment with said line of abutment and the wall of one of said tub structures transverse to said line of abutment and into an intermediate position to confine said wringer within the marginal and vertical dimensions of one of said tub structures.

4. In combination, a pair of abutting tub structures, a wringer mounting receiving recess at one end of the line of abutment of said tub structures and extending on each side thereof, an L-shaped wringer mounting column having its short leg lying in a plane transverse to the portion received in said recess, a wringer structure carried by said short leg of said mounting column, said mounting column being adapted to carry said wringer into alignment with the line of abutment of said tub structures and the wall

of one of said tub structures transverse to said line of abutment, as well as to an intermediate position to cause said short leg and said wringer to be received within the vertical and marginal confines of one of said tub structures for storage.
